UNITED STATES PATENT OFFICE.

THOMAS WRIGHT, OF SOUTH NORWICH, COUNTY OF OXFORD, ASSIGNOR TO THE OTTO SWEEPER COMPANY, (LIMITED,) OF OTTERVILLE, ONTARIO, CANADA.

COMBINED CAMP-CHAIR AND CANE.

SPECIFICATION forming part of Letters Patent No. 295,216, dated March 18, 1884.

Application filed May 10, 1882. (No model.)

To all whom it may concern:

Be it known that I, THOMAS WRIGHT, of the township of South Norwich, in the county of Oxford, in the Province of Ontario, Dominion of Canada, mechanic, have invented a new and useful invention to be known and described as "Wright's Tourist's Chair and Cane," the particulars of which are fully set forth in the following specification and accompanying drawings, in which—

Figure 1 is a perspective view of my invention when being used as a chair. Fig. 2 is a front view of the same when being used as a cane. Fig. 3 is a side view of the central staff, showing the hinge for attaching the seat and the metallic clamp for attaching the movable legs, and Fig. 4 is one of the movable legs.

The object of my invention is to furnish an article which shall be sufficiently light that it can be carried in the hand and used as a walking-stick, and at the same time, when unfolded and placed in proper position, shall be sufficiently strong to be used as a chair or seat on which the tourist may sit down to rest.

In the drawings, A is the central staff. B is the seat of the chair. C C are movable legs. D is the hinge or loop which secures the seat B to the central staff, A. E is a metallic clamp secured to the central staff, A, by means of rivets or screws, to which the movable legs C C are loosely fastened or pivoted in such manner as that the ends of the legs will move freely in any direction required, said legs being also provided with pins or points at their upper ends. F is a bow, which answers the double purpose of a back for the chair and a handle for the cane. When used as a cane, the seat B is folded up, so that its plane is parallel with the central staff, A, to which it is secured by the hinge or loop D. The movable legs C

C are turned on their pivots so as to be parallel with the central staff, A, and the plane of the seat B, and are fastened to the central staff by a ring near the bottom.

When it is desirable to use my invention as a chair, the rings at the top and bottom are thrown off and the seat B is turned down until its plane is in a horizontal position, and the movable legs C C are turned on their pivots until the pins in the upper ends of them enter into holes made to receive them in the outer edge of the rim of the seat. In this position it becomes a strong trestle or cross-legged stool, while the handle F and upper part of the central staff, A, form a back to the seat.

My invention may be made of any suitable material and in any style of art, either plain and simple or rich and elaborately finished.

Having thus described my invention, what I claim as new, and desire to secure by Letters Patent, is—

1. A combined camp-chair and cane composed of the following elements, namely: central staff, A, loop D, clamp E, pivoted legs C C, seat B, and bow-handle F, constructed and arranged substantially as shown and described.

2. In a combined chair and cane composed, essentially, of a central staff and movable legs, the bow-handle B, also forming a back for the chair, substantially as described.

3. In a combined chair and cane, the seat B, hinged to the central staff by means of a loop, D, substantially as described.

Otterville, March 31, A. D. 1882.

THOMAS WRIGHT.
